UNITED STATES PATENT OFFICE

EDWARD F. BUENGER, OF CHICAGO, ILLINOIS, ASSIGNOR TO WILSON-JONES COMPANY,
OF CHICAGO, ILLINOIS, A CORPORATION OF MASSACHUSETTS

EXPANSIBLE POST BINDER

Application filed November 8, 1928. Serial No. 317,989.

This invention relates to an expandable post binder and concerns itself primarily with sectional posts which can be simultaneously extended a predetermined extent by means of a rotatable element and which can be further extended by the addition of post sections.

The invention comprises the novel structure and combinations of parts hereinafter described and more particularly pointed out and defined in the appended claims.

In the accompanying drawings, which illustrate a preferred embodiment of this invention and in which similar reference numerals refer to similar features in the different views:

Figure 1 is a top plan view of a loose leaf binder involving this invention.

Figure 2 is an end elevational view of the binder.

Figure 3 is an enlarged sectional view taken upon the line III—III of Figure 1.

Figure 4 is an enlarged view from below of the lower clamping member with the cover plate removed.

Figure 5 is an enlarged sectional view which is taken longitudinally through the clamping members of the binder.

Figure 6 is a top plan view of the binder with the upper cover member and its clamping member removed.

Figure 7 is an enlarged fragmentary sectional view through an impaling post illustrating the manner of adding additional post sections.

Figure 8 is a sectional view taken upon the line VIII—VIII of Figure 5.

The binder to which this invention is applied consists of a lower clamping member 1 and an upper clamping member 2 which is made of sheet-metal in hollow box-like form. Cover members 3 are hinged to the clamping members 1 and 2 as is usual in the art.

The lower clamping member consists of a plate and a channel-like member 1a which is secured to said plate-member by screws 4. Within the clamping member 1 are U-shaped brackets 5 which are provided with upper attaching flanges 6 secured to the plate 1. These U-shaped brackets are provided with cylindrical bearings 7 shown in Figure

4 for receiving a shaft 8, one end of which extends through the end of the clamping member. The projecting end of the shaft 8, which is indicated as 8a is of polygonal form for the purpose of receiving a key or wrench. 55

A pair of screws 9 are rotatably secured in the clamping member 1. The lower portions of these screws are enlarged. The enlarged portion of each screw has a worm 10 fixed thereon. The lower end of each screw has a reduced journal portion 11 which extends into an aperture or socket 12 in the bottom of the U-shaped bracket 5. Just above the enlarged bottom of the screws 9 there is a smooth portion 13. A sleeve 14 concentric with each screw 9 is fixed in the plate 1 against rotation. Impaling posts 15 are provided with lower reduced portions 16 which fit into the sleeve members 14, and these impaling posts are internally threaded for receiving the screws 9. 60 65 This reduced portion 16 is provided with a groove 17 which is best shown in Figure 8. And the sleeve 14 is provided with an inwardly directed bead 18 that fits into said groove. The aforementioned rod 8 is provided with a pair of worm wheels 19 which mesh with the worms 10 on the screws 9. 70 75

It will be obvious that when the rod 8 is rotated in the proper direction, the two screws 9 will be rotated and will cause the posts 15 to be elevated for expanding the binder. In this connection it will be noted that the smooth portions 13 of the screws are located in the bottom of the sleeves 14 so there is no tendency to rotate the sleeves. On the other hand, the sleeve members 14 on account of their engagement of the beads 18 in the grooves 17, prevent the posts 15 from rotating, with the result that when the screws 9 are rotated the posts 15 are compelled to move longitudinally of the screws 9. The posts 15 can also be retracted from an expanded position for the purpose of contracting the binder. In the drawings, however, they are shown in their most contracted position. 80 85 90 95

The posts 15 have threaded sockets 20 in their upper ends for receiving the threaded stems of post sections 21 which are also provided with threaded sockets 22, at their up- 100

per ends for receiving screws 23 which clamp the upper clamping member 2 upon the posts. In this connection it will be noted that the upper clamping member 2 is indented for receiving the heads of the screws 23 in order that the same will not project above the surface of the clamping member. It will also be noted that the lower part of the upper clamping member is provided with suitable apertures for receiving the posts.

In referring to Figure 7, it will be noted that a second post section 24 has been added to the post shown in Figure 5 and the screw 23 secures the upper clamping member to the post section 24 in a manner similar to that shown in Figure 5. In other words, Figure 7 illustrates the addition of post sections to increase the capacity of the binder beyond the extent allowed by the adjustable posts shown in the first form.

The leaves which are illustrated at 25 may be inserted or removed from the posts without removing the upper cover. To this end the apertures in the sheets that receive the posts are provided with slots 26 extending to the edge of the sheet through which the posts may be forced.

A binder involving this invention has several advantages over the old sectional form of post for the reasons that the binder may be expanded within certain limits by merely rotating the worm shaft 18. It will also be appreciated that the clamping head 2 may be readily contracted, to firmly bind the sheets in the binder when the binder is filled with leaves to an extent that requires some contraction. In the old sectional posts it was impossible to contract the binder head to tightly embrace the leaves under any conditions.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. In a loose leaf binder, a hollow clamping head, a pair of sleeves secured to said head, a post slidably mounted in each sleeve, said posts and sleeves each having interengaging parts for preventing relative rotation thereof, a screw extending into each post and means in the hollow clamping member for rotating said screws for causing relative sliding movement between said posts and sleeves.

2. In a loose leaf binder, a clamping member, a pair of posts extending from said clamping member, a second clamping member having apertures for receiving said posts, said second clamping member provided with indentations for resting on top of said posts and screws having their heads in said inden-

tations for securing said second clamping member to said posts.

3. In a loose leaf binder, a clamping member, a pair of sleeves secured to said clamping member, a screw extending into each sleeve from said clamping member, a post reciprocal in each sleeve and in threaded relation with the screw therein, cooperative means between each sleeve and post for preventing relative rotation thereof and means for simultaneously rotating said screws for the purpose set forth.

4. In a loose leaf binder, a hollow clamping member, a plurality of brackets positioned in said member, a rotatable shaft supported by said brackets, gears carried by said shaft and positioned in said brackets in such a manner as to prevent lateral movement therewith, a plurality of screws extending into said clamping member and having their end portions disposed in said brackets, each of said screws having a gear in mesh with one of the aforementioned gears, a post carried by each screw, and means for confining said posts for reciprocating movement by said screws.

5. In a loose leaf binder, a plurality of clamping members, a plurality of sleeves secured to one of said members, a plurality of sectional posts secured to another of said members and slidably disposed in said sleeves, rotatable members extending into said sleeves and having their upper ends threadedly connected to said posts, and means for actuating said rotatable members for slideably moving said posts in said sleeves.

In testimony whereof I have hereunto subscribed my name at Chicago, Cook County, Illinois.

EDWARD F. BUENGER.
